UNITED STATES PATENT OFFICE.

MOSES L. ANDREW, OF DELHI, OHIO.

VARIETY BORING-MACHINE.

SPECIFICATION forming part of Letters Patent No. 733,115, dated July 7, 1903.

Application filed May 31, 1902. Serial No. 109,710. (No model.)

To all whom it may concern:

Be it known that I, MOSES L. ANDREW, a citizen of the United States, residing at Delhi, Hamilton county, Ohio, have invented certain new and useful Improvements in Variety Boring-Machines, of which the following is a specification.

This invention, pertaining to improvements in machines for variety boring or producing in one or more groups of parallel holes in adjustable relationship to each other, will be readily understood from the following description, taken in connection with the accompanying drawings, in which—

- 15 Figure 1 is a front elevation of a machine exemplifying my invention; Fig. 2, a vertical section of the same in the plane of line *b* of Fig. 1; Fig. 3, a vertical section of a portion of the machine in the plane of line *f* of Fig. 1; Fig. 4, a vertical section of a portion of the machine in the plane of line *a* of Fig. 1; Fig. 5, a perspective view of a portion of the table, showing the same in vertical transverse section in the plane of line *c* of Fig. 1; 20 Fig. 6, a horizontal section of the boring-head 9 in the plane of line *d* of Figs. 1 and 7; Fig. 7, a vertical section of the boring-head 9 in the plane of offset line *g* of Fig. 6; Fig. 8, a perspective view of the boring-head 11; Fig. 9, a horizontal section of the boring-head 11 in the plane of line *e* of Fig. 1; Fig. 10, a horizontal section of the boring-head 10 in the plane of line *e* of Fig. 1; Fig. 11, a plan of boring-heads 12 and 13; and Fig. 12 a vertical section of boring-head 12 in the plane of lines *h* of Fig. 11.

In the drawings, 1 indicates a column; 2, a horizontal rail supported by the top of the column and presenting a flat front face and having a central horizontal slot; 3, brackets projecting upwardly from the ends of the rail; 4, a driving-shaft mounted in brackets 3, its axis being parallel with and forward of and above the rail; 5, driving-pulleys on each end of this shaft; 6, a rod fixedly supported by the brackets 3, parallel with the driving-shaft; 7, a series of bevel-gears splined upon the driving-shaft and having circumferential-grooved hubs; 8, thrust-bearings engaging the grooves of gears 7 and adjustably secured to rod 6; 9, 10, 11, 12, and 13, a series of bor-

ing-heads secured to the face of the rail and adjustable along the same and arranged to carry and give motion to downwardly-projecting boring-bits; 14, a vertical guideway on the face of the column; 15, a knee mounted for sliding motion on this column; 16, a screw mounted on the column and engaging the knee and provided with mechanism for turning it by hand and serving as means for the vertical adjustment of the knee upon the top; 17, a table-stem mounted to slide vertically in the forward portion of the knee; 18, the table, the same extending along under the series of boring-heads and being united to table-stem 17 by a horizontal pivot at right angles to the length of the table; 19, diagonal braces extending from the lower portions of the table-stem upwardly and outwardly into pivotal connection with the table and being pivotally connected with the table-stem at selective points in the length of the braces; 20, a longitudinal slot with undercut side walls in the upper surfaces of the table, the portion of the table forming the floor of this groove being of a skeleton or open form; 21, wooden blocks firmly fitting the groove 20 and adjustable along the same and having their upper surfaces flush with the upper surface of the table; 22, a treadle pivoted in the base of the column and projecting forwardly; 23, a rock-shaft journaled in the knee between the column and the table-stem; 24, a lever fast on this rock-shaft; 25, a link connecting the forward end of this lever with the table-stem; 26, a link extending upwardly from the treadle; 27, a screw connecting link 26 with the rear end of lever 24 and forming a prolongation of link 26 and serving as a means by which the length of the chain-link thus formed may be adjusted; 28, a rearwardly-projecting weighted lever fast on rock-shaft 23 and serving in counter-balancing the weight of the table and the work to any desired degree; 29, a forwardly-projecting hand-lever fast on rock-shaft 23; 30, a vertical rod carried by the table-stem and working through an eye in the knee; 31, a spring upon this rod and compressing between a collar thereon and the eye of the knee through which it works; 32, a pair of vertical rods, one at each end of the rail,

their lower ends resting on the floor and their upper ends engaging lugs on the rail, and 33 set-screws binding these rods in the lugs.

The work to be bored is placed upon the 5 table and the table fed upwardly to the boring-bits, either by hand or foot. Spring 31 is adjusted to be compressed to a proper degree by the time the table has been lifted to the desired limit, so that when the boring is 10 is done and the feeding pressure removed the spring will aid in producing the descent of the table and the work and at the particular time when the clinging of the work to the bits is the greatest. It is to be understood 15 that the table is to be provided with such work-gripping devices and such feed-stops as are usual in vertical boring-machines. With the table set as indicated in the drawings the boring will be done at right angles to the 20 face of the table. By disconnecting the braces 19 and reconnecting one of them at a new point in its length the table may be swiveled on a horizontal axis, so that boring may be done at an angle to the face of the 25 table. The open character of the central portion of the table at the groove 20 provides freedom for the dropping of the boring-chips, and the blocks 21 give proper table support to the work. The blocks 21 being adjustable along the length of the table may generally be set to positions between the bits so as not to interfere with the dropping of the chips; but, if necessary, they may be bored or mortised to permit the chips to fall 30 through them. The boring-heads are adjustable along the length of the rail, so that the borings produced by their individual spindles may be in adjustable relationship to each other. The motion is given to the boring-spindles through bevel-gears driven by 35 the bevel-gears 7, which are splined to the driving-shaft, these gears 7 being adjusted along the driving-shaft to suit the selected positions of the boring-heads, and in thus adjusting these bevel-gears upon the driving-shaft the thrust-bearings 8 are appropriately 40 adjusted upon the rod 6. Boring may be done by all of the heads at once, or one or more heads may be thrown out of action by 45 shifting the appropriate ones of the bevel-gears 7 out of mesh with the gears which they drive. For light work the driving-shaft may receive its motion from the driving-pulley at one end of the shaft, while for extra-heavy 50 work the pulleys at both ends may be employed, thus avoiding the necessity for employing a very wide or tightly-strained belt at all times. The general support to the rail is of course given by the column; but the 55 support of its ends is reinforced by the rods 32. In setting up the machine the rail is allowed to take its natural position as determined by the column, after which the set-screws 33 are tightened upon the rods, thus 60 giving the ends of the rail additional supports, adapting themselves to the inequalities of the shop-floor.

Of the boring-heads head 9 is adapted for the production of a longitudinal row of holes in fixed relationship to each other. Head 10 70 is adapted to bore two holes in a line at right angles to the length of the table, the distance between the holes being adjustable. Head 11 is adapted to bore two holes in a line parallel with the length of the table, the distance 75 between the holes being adjustable. Head 12 is adapted to bore two holes a fixed distance apart in a line either parallel with or at right angles to the table or at intermediate angles. Head 13 is adapted to bore a single 80 hole at various points transverse to the length of the table. These various heads will now be described in detail.

Proceeding further with the drawings and giving special attention to Figs. 8 and 1, the 85 construction of boring-head 11 is as follows: 34 indicates a saddle seating against the face of the rail and gibbing under its bottom and over its top and adjustable along the rail; 35, an arm projecting therefrom parallel with 90 the rail; 36, a boring-spindle journaled in the saddle with its axis in the vertical plane of that of driving-shaft 4, its lower end being provided with a bit-socket; 37, a bevel-gear 95 fast on the upper end of this boring-spindle and adapted to be engaged by one of the bevel-gears 7, splined upon the driving-shaft; 38, a pinion fast on the boring-spindle; 39, a bracket sliding on arm 35 of the saddle and bolted thereto and having a bearing for the 100 second boring-spindle; 40, the second boring-spindle, journaled in the bearing of this bracket; 41, a pinion fast on boring-spindle 40 in the horizontal plane of pinion 38; 42, a segment mounted on bracket 39 and angularly adjustable centrally to boring-spindle 105 40; 43, an intermediate pinion carried by this segment and adapted to engage pinions 38 and 41, and 44 a bolt clamping the saddle to the rail. The saddle may be adjusted along 110 the rail to bring boring-spindle 36 to the desired position, and then that one of bevel-gears 7 which is to drive it, together with its thrust-bearing, is to be properly adjusted. Bracket 39 is then to be adjusted to the 115 desired distance to give the desired distance between boring-spindles 36 and 40. Segment 42 is then to be angularly adjusted to bring its pinion 43, which constantly engages pinion 41, into engagement with pinion 38. 120 If boring-spindle 36 alone is to be used, then intermediate gear 43 may be thrown out of gear with pinion 38, thus avoiding the loss of power which would be due to the idle driving of boring-spindle 40. The entire boring-head 125 may, if desired, be entirely removed from the rail in case it is not needed and its presence interferes with the proper relationship of the boring-heads at each side of it. This may also be said of all of the boring-heads upon 130 the rail.

Boring-head 10 needs but brief description, and reference may be had to Figs. 1, 2, and 10 of the drawings, in which 45 indicates the

saddle of this boring-head; 46, its projecting arm, which in this case projects at right angles with the rail instead of parallel with it; 47, the shifting bracket for the second boring-spindle; 48, the segment for the intermediate gear; 49, the main boring-spindle of the head, the same being in the vertical plane of the axis of the driving-shaft, and 50 the second boring-spindle, journaled in bracket 47. The general description which has been given of boring-head 11 will apply in the present case, the only difference being that in the present case the second boring-spindle is adjustable to and from the rail instead of parallel with it.

Boring-head 12 will be readily understood from Figs. 1, 11, and 12, in which 51 indicates the main boring-spindle, journaled in the saddle, as in the previous cases; 52, the bracket for the second boring-spindle, the same being mounted for oscillation upon an axis coinciding with that of spindle 51; 53, the second boring-spindle; 54, the intermediate pinion, carried by the bracket in which is journaled the second boring-spindle, there being no adjusting-segment for this gear in the present case; 55, a sleeve forming the lower bearing for spindle 51 and the lower and clamping pivot uniting bracket 52 to the saddle of the head, and 56 a clamp-nut screwing on the lower end of this sleeve. Bracket 52 may be swung as desired to adjust the second boring-spindle 53 in a portion of a circle about spindle 51 and then clamped by nut 56.

Boring-head 13 may be understood from Figs. 1 and 11, in which 57 indicates the swinging bracket carrying the adjustable boring-spindle, which in this case is the only boring-spindle of the head, the saddle itself having no spindle; 58, a short vertical spindle journaled in the saddle in the vertical plane of the axis of the driving-shaft and in the center of oscillation of bracket 57 and driven from the driving-shaft through one of bevel-gears 7 thereon; 59, the boring-spindle of this head, journaled in bracket 57 and directly geared to shaft 58; 60, the two pinions connecting shaft 58 and spindle 59, and 61 a combined pivot and clamping bolt uniting bracket 57 with its saddle and serving to clamp the bracket in adjusted position. As this head carries but a single boring-spindle, the gearing driving it is direct—that is to say, there is no intermediate pinion between the boring-spindle and its mating vertical shaft.

Boring-head 9 will be understood from Figs. 1, 6, and 7, in which 62 indicates a multiple bearing projecting forward from the base of the saddle and having a number of vertical bearings for boring-spindles; 63, a pair of vertical shafts journaled in the saddle in the vertical plane of the driving-shaft and driven therefrom by a couple of the bevel-gears splined thereon, these two shafts not being boring-spindles, but terminating in bearings in the multiple bearing-piece 62; 64, the boring-spindles journaled in the multiple bearing-

62, the illustration showing ten of these boring-spindles divided into two groups of five each, each group to be driven by one of the shafts 63; 65, intermediate pinions having spindles journaled in the multiple bearing 62; 66, the spindles of these intermediate pinions, these spindles having no collars at their lower ends; 67, pinions on the two shafts 63 in a horizontal plane of the intermediate pinions, and 68 the pinions on the upper ends of the boring-spindles 64. Each of shafts 63 drives two of the spindles 64 by direct gearing and drives the remaining three of its group of spindles through the intermediate pinions. The driving of the entire lot of ten bearing-spindles is thus divided between two of the bevel-gears upon the driving-shaft, and either of the two groups of five spindles will be thrown out of action by disconnecting the bevel-gear which drives that group. By lifting appropriate ones of the intermediate pinions 65 out of the multiple bearing some of the boring-spindles in each group may be thrown out of action, and the arrangement illustrated is obviously such that, considering the lot of ten spindles, all may be in use, or five of them may be thrown out of use by disconnecting one of the bevel-gears, or one or more of the spindles in each of the groups of five may be thrown out of use by removing the appropriate intermediate pinions.

It will be observed that the construction of the machine is such that either one or a plurality of the boring-heads may be employed—that is to say, any given boring-head may be removed from the rail and another substituted. Some of the spindles or shafts of the boring-heads to which the motion is imparted from the splined shaft require to be driven in one direction and some in another in order to get the proper direction of motion for the bits, and the bevel-gears 7 upon the splined shaft may be arranged to produce the desired direction of motion; but to reverse these bevel-gears on the splined shaft requires the removal of the shaft from its bearings, an undesirable procedure when one boring-head is substituted for another upon the rail. Thus a boring-head may be removed from the rail and another substituted which would not receive the proper direction of motion from the bevel-gear upon the splined shaft; but the splined shaft is provided with pulleys at each end and may thus be arranged to be driven by an open belt at one end and a crossed belt at the other end, thus providing for either direction of motion for the splined shaft. Again, the machine may give employment to a single boring-spindle requiring little power and capable of being driven by a narrow belt; but when a multiplicity of spindles is employed the power may be increased by employing a second driving-belt in connection with the pulleys at the opposite end of the splined shaft. In practice the overhead shafting from which these machines receive their

motion is arranged with pulleys by which motion can be put to the splined shaft in either direction of rotation or any one direction of rotation with the power due to a double belt.

5 I claim as my invention—

1. In a variety boring-machine, the combination, substantially as set forth, of a column, a rail supported thereby, boring-heads and driving mechanism supported by the rail, a feed-table carried by the column, rods extending from each end of the rail downward to the floor, and coupling devices adjustably connecting the upper ends of the rods with 15 the rail.

2. In a variety boring-machine, the combination of a column, a feed-table carried thereby, a rail carried by the column, boring-heads adjustable upon the rail, boring-spindles in 20 the heads and provided with bevel-gears, a driving-shaft journaled in the rail over the boring-heads, bevel-gears adjustably splined to the shaft and adapted to engage the bevel-gears of the boring-spindles, whereby the appropriate gear on the shaft may be brought 25 into engagement with a boring-spindle gear to drive it in a predetermined direction, a support above the rail, and thrust-bearings adjustably secured to said support and engaging the hubs of the bevel-gears.

3. The combination of a standard, a rail carried thereby, a boring-head adjustable upon the rail, a spindle carried in the head, a drive-shaft parallel with the rail, a driving connection for the spindle rotating with and adjustable upon the drive-shaft, a support alongside the drive-shaft, and a thrust-bearing adjustably secured to said support and engaging the driving connection upon the drive- 35 shaft.

4. In a variety boring-machine, the combination, substantially as set forth, of a col-

umn, a feed-table supported thereby, a rail supported by the table, a driving-shaft supported above and forward of the rail, a saddle mounted for adjustment along the rail, a boring-spindle journaled in the saddle, a bevel-gear on the upper end of the boring-spindle, a bevel-gear splined on the driving-shaft and having a circumferentially-grooved hub, a rod supported by the rail parallel with the driving-shaft, and a thrust-bearing adjustably secured to the rod and engaging the groove of the bevel-pinion.

5. In a variety boring-machine, the combination, substantially as set forth, of a column, a feed-table mounted thereon, a rail supported by the column, a saddle mounted on the rail, a vertical shaft journaled in the saddle, a driving-shaft carried by the rail and 50 bevel-geared to said vertical shaft, a multiple bearing at the base of the saddle, a group of boring-spindles mounted in said multiple bearing, a pinion upon said vertical shaft, pinions upon said boring-spindles, intermediate pinions engaging the pinions of the boring-spindles, and spindles for said intermediate gears journaled in said multiple bearing and upwardly removable therefrom with their pinions.

6. The combination of a standard, a rail carried thereby, a boring-head adjustable upon the rail, a spindle carried in the head provided with a bevel-gear, a drive-shaft alongside the rail, a bevel-gear rotating with and adjustable upon the drive-shaft, a support alongside the drive-shaft, and a thrust-bearing adjustably secured to said support and engaging said bevel-gear upon the drive-shaft.
